UNITED STATES PATENT OFFICE.

ROBERT TEMPLE, OF DENVER, COLORADO.

DESIGN FOR A GAS-ENGINE FRAME.

SPECIFICATION forming part of Design No. 26,846, dated March 30, 1897.

Application filed January 26, 1897. Serial No. 620,834. Term of patent 7 years.

To all whom it may concern:

Be it known that I, ROBERT TEMPLE, a citizen of the United States of America, residing at Denver, in the county of Arapahoe and State of Colorado, have invented a new and original Design for a Gas-Engine Frame; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a design for a frame for gas or gasolene engines; and it consists of the features hereinafter described and claimed, all of which will be fully understood by reference to the accompanying drawings, in which is illustrated an embodiment thereof.

In the drawings, Figure 1 is a front view

of my design, and Fig. 2 is a side view of the same.

The leading feature of my design consists of a base having two upright arms separated 25 by a suitable space.

The numeral 5 designates the base, 6 the upright arms, and 8 the space above the base, separating the arms 6. The sides of the frame are provided with planing-strips 9. The arms 30 6 are provided with bearings 10, cast integral therewith.

Having thus described my invention, what I claim is—

The design for a gas-engine frame as herein 35 shown and described.

In testimony whereof I affix my signature in presence of two witnesses.

ROBERT TEMPLE.
